P. E. EDELMAN

RADIO VACUUM TUBE CIRCUITS

Filed June 5, 1922

INVENTOR
Philip C. Edelman

UNITED STATES PATENT OFFICE.

PHILIP E. EDELMAN, OF NEW YORK, N. Y.

RADIO VACUUM-TUBE CIRCUITS.

Application filed June 5, 1922. Serial No. 566,131.

The invention relates to a radio receiving circuit in which substantially continuous oscillations may be obtained in the plate circuit only without feeding back energy to the grid circuit as is customary in the prior art. A preferred embodiment of my present invention and examples of suitable modifications thereof are shown in the accompanying circuit diagrams of which—

10 The figure is a circuit of a receiving set. Similar numerals refer to similar portions throughout the view.
 In the prior art when a vacuum tube is connected to an oscillatory circuit, it is customary to in some manner feed back a portion of the energy in the plate circuit to the grid circuit, such for example as shown in U. S. Patent 1,113,149 dated October 6, 1914. The present invention is different therefrom
 15 and may be used with either two, three or four element vacuum tubes such as are commonly known in the radio art at the present time. In U. S. Patents Nos. 803,684, November 7, 1905; 841,387, January 5, 1907, and 879,532, February 18, 1908, suitable types of vacuum tubes are shown.

20 My present invention may be used as an attachment to the circuits of said last named U. S. patents, or may be preferably used as shown in the accompanying drawings.

25 I have set up such circuits and obtained very good results, there being a marked absence of undesirable regeneration and capacity effects such as are experienced when
 30 a circuit of the type shown in U. S. Patent No. 1,113,149 above referred to is used.

35 Instead of the usual feeding back of a portion of the energy of the plate circuit to the grid circuit, the grid circuit indicated in the figure has a wire 11 connected to grid 12 and wire 11 connects to wire 10 and to wires 14 and 15 of coil 16, while wire 10 also connects to coil 5 and wire 4, so that the grid circuit is completed via coil 7, wire
 40 8, wire 36, and filament 29 of vacuum tube 13. In accordance with this invention satisfactory results are obtained as hereinafter set forth. The loudness and definition of the sounds heard in the receiver are remarkably
 45 improved and noticeably free from distortion as is caused in the usual regenerator circuit of the prior art.

50 The present invention contemplates improvements in the arrangement and connections of the apparatus, and to this end I have modified the usual circuit of the prior

art as shown in the drawings and explained in the following description:—

I depart from the customary arrangement in such circuits and by referring for example 60 to the figure, it will be noticed that an inductance coil 19 is connected in the plate circuit; coupled to this inductance coil is a short-circuited inductance coil 14; preferably both of these coils are constructed alike, 65 and with a certain small distributed capacity in the winding such that each coil has a broad range of natural periods of vibration.

70 For example, in the circuit tuned to 360 meters, I prefer to use a coil of 90 turns of No. 26 D. C. C. wire for the coil 19. These turns of wire are wound in a groove approximately one-half inch deep and with an inside diameter at bottom of winding of three 75 and a half inches. The coil 16 is similarly wound on an insulating disk of the same dimensions and is short-circuited by the wires 14, 15. The coil 16 must be closely coupled to the coil 19, the amount of coupling depending on the characteristics of the vacuum tube 13 in the circuit. For most soft tubes the coupling should be very tight, but for a good sensitive tube a lesser coupling works best. The wires 14, 15 must be short-circuited otherwise when the wire 14 is open-circuited, the circuit acts like a straight 80 vacuum tube detector without amplifying effects.

85 In addition the wires 14 and 15 must be connected between the inductance 5 and the condenser 3.

90 It is to be understood that the plate circuit coil 19 is not inductively coupled with either of the coils 5 or 7 in the grid circuit. 95 The coils 16 and 19 are so designed as to be resonant to a broad band of frequencies.

99 Referring now to the figure, the usual single circuit receiving diagram is shown with tuning variometer 5, and tuning condenser 3. For 360 meters the variometer should have 40 turns on each winding and the condenser 3, a capacity of .001 microfarad. The small condenser 33 of .001 microfarad is not essential and may be omitted as usually the wires 22, 26 afford all the capacity necessary to by-pass the radio frequency energy in the plate circuit. Ordinarily there is no audio frequency hum heard in the telephone receivers 23, 24, but 110 on some tubes in case the filament 29 is burned very bright, there will be a slight

audible frequency hum in the receivers which, however, is not loud enough to interfere with the usual signal received. The balance resistance 28 shown in the vacuum tube 5 may be of the type described in my co-pending application, Serial No. 566,132 filed June 5, 1922, and can be replaced by an ordinary filament resistance without in any way affecting results. It will be seen, however, 10 that the naturally resonant coil 19 closely coupled to the naturally resonant coil 16, which is short-circuited by the wires 14, 15, serves as a radio frequency regenerative circuit in such manner that the plate circuit 15 acquires amplifying and oscillatory properties without being coupled to the grid circuit.

In the circuit in the figure, a good condenser with grid leak may be connected in series 20 in the wire 10 without detriment to the behavior of this circuit, and in fact such a condenser with grid leak is advisable with certain makes of vacuum tube 13. The connection between short-circuited coil 16 and the wire 10 may be omitted under certain conditions with equally good results, but in general the circuit works best when the short-circuited coil 14 is connected as shown in the figure.

30 Various changes and modifications can be made by anyone skilled in this art within the spirit of this invention and within the scope of the appended claims, as I have shown by way of example a suitable embodiment as applied to a simple vacuum tube circuit and it will be readily understood that the invention is operative in other circuits such as, for instance, a circuit employing a plurality of vacuum tubes in progressive or cascaded connection.

Inasmuch as the diagrams are self-explanatory in connection with the above description, it will be obvious that numerous changes may be made within the scope of the appended claims.

What I claim is:

1. A vacuum tube radio system having an antenna circuit, a vacuum tube connected thereto, a radio frequency transformer connected with its primary winding in the plate circuit of said vacuum tube, with the secondary of said radio frequency transformer substantially short-circuited and connected by a single wire to said antenna circuit.
2. A vacuum tube radio system having a grid circuit containing a grid condenser and grid leak resistance, a plate circuit containing in series a direct current energy supply and translating device, and a primary winding of a radio frequency transformer constructed to have such distributed capacity in

its winding as to make said winding naturally resonant, the secondary of said radio frequency transformer being substantially short-circuited through a low resistance, and connected by a single wire to said grid circuit so as to afford a naturally resonant plate circuit which has oscillatory and amplifying properties without feed back coupling to said grid circuit.

3. A radio receiving circuit including a three electrode vacuum tube having a grid circuit and a plate circuit, a radio frequency resonant inductance coil in said plate circuit, a substantially short-circuited inductance coil coupled to said coil in said plate circuit, and a wire connecting such short-circuited inductance to the grid circuit to which said vacuum tube is connected.

4. In a radio circuit comprising a vacuum tube, a tuned input circuit, and an output circuit therefor including an inductance, means to control the amplifying action of said circuit, said means comprising a substantially short circuited coil connected to said input circuit and adapted to react on said inductance and comprise therewith an automatically varied resistance as the input circuit is tuned for different frequencies.

5. In a radio circuit employing a vacuum tube having a grid and a plate circuit, the improvement which comprises an inductance coil in said plate circuit with a second coil comprising a plurality of turns of wire closely coupled thereto to serve as a regulator for the oscillatory currents in said plate circuit flowing thru said first inductance coil, said first inductance coil having a fixed relation with respect to said second coil, and said second coil having its terminal ends substantially short circuited whereby the reactance effect of said second coil is entirely and automatically that due to the second coil of itself according to the current flowing in said first inductance coil.

6. In a radio circuit including a three element vacuum tube, the improvement which comprises a plate coil in series with the plate of said vacuum tube, a substantially short circuited coil closely coupled to said plate coil and constructed to have capacity with respect to said plate coil, and a connection from the grid of said vacuum tube to said short circuited coil whereby said capacity between said two coils is shunted around said grid and said plate, to control the effective amplification of said vacuum tube.

In witness whereof, I have hereunto set my name this 27th day of May, 1922 at New York city, county and State of New York.

PHILIP E. EDELMAN.
